UNITED STATES PATENT OFFICE.

JOHN BEISWANGER, OF STEUBENVILLE, OHIO, ASSIGNOR TO GILL BROTHERS COMPANY, OF STEUBENVILLE, OHIO, A CORPORATION OF WEST VIRGINIA.

DESIGN FOR A LAMP-CHIMNEY.

54,577.

Specification for Design.

Patented Mar. 9, 1920.

Application filed October 15, 1919. Serial No. 330,926. Term of patent 14 years.

To all whom it may concern:

Be it known that I, JOHN BEISWANGER, a citizen of the United States of America, and resident of Steubenville, county of Jefferson, State of Ohio, have invented a certain new, original, and ornamental Design for a Lamp-Chimney, of which the following is a specification.

In the accompanying drawing I have illustrated a lamp-chimney, constructed in accordance with my invention.

The figure is a side elevation of the same.

The device consists of a transparent glass chimney, having a cylindrical central portion (1), terminating at the top in a curved shoulder (2), which tapers to a reduced neck portion (3), having a scalloped flaring top

edge (4). The cylindrical portion terminates below in a curved shoulder (5), where the chimney is reduced in diameter, forming a cylindrical insert, or base, (6). The cylindrical portion (1) bears an ornamental scroll (7).

Having thus described and illustrated my invention, I claim:

The ornamental design for a lamp-chimney, substantially as shown and described.

Signed by me at Steubenville, Jefferson county, Ohio, this 15th day of September, 1919.

JOHN BEISWANGER.
